[57] CLAIM

The ornamental design for a foldable toothbrush, as shown and described.

DESCRIPTION

FIG. 1 is a front end elevational view of a foldable toothbrush showing my new design, shown in its unfolded state;

FIG. 2 is a side elevational view thereof;

FIG. 3 is a top plan view thereof;

FIG. 4 is a bottom plan view thereof;

FIG. 5 is an elevational view of the side opposite that shown in FIG. 2;

FIG. 6 is a rear elevational view thereof;

FIG. 7 is a side elevational view thereof shown in its folded state, the opposite side being a mirror image;

FIG. 8 is a top plan view thereof;

FIG. 9 is a bottom plan view thereof;

FIG. 10 is a front end elevational view thereof; and

FIG. 11 is a rear end elevational view thereof.
